UNITED STATES PATENT OFFICE.

WILLIAM M. MURRAY, OF CANAJOHARIE, NEW YORK.

WINDOW-SHADE GUIDE.

1,216,594.

Specification of Letters Patent. Patented Feb. 20, 1917.

Application filed April 10, 1916. Serial No. 90,144.

To all whom it may concern:

Be it known that I, WILLIAM M. MURRAY, a citizen of the United States, residing at Canajoharie, in the county of Montgomery and State of New York, have invented certain new and useful Improvements in Window-Shade Guides; and I do declare the following to be a full, clear, and exact description of the invention, such as will enable others skilled in the art to which it appertains to make and use the same.

This invention relates to window shade and curtain guides for use in connection with the usual spring roller shades, the principal object of the invention being to provide a simply constructed device of this character which can be inexpensively manufactured from sheet or other light metal.

With this general object in view, my invention resides in the novel features of construction, combination and arrangement of parts which will hereinafter be more particularly described and claimed and shown in the drawings wherein:

25 Figure 1 is a front elevation of the upper portion of a window frame having an ordinary shade roller curtain mounted thereon, showing one form of my invention applied;

Fig. 2 is a detail perspective view of one 30 of the improved shade guides;

Fig. 3 is an elevation of the guide shown in Fig. 2;

Fig. 4 is a view similar to Fig. 1 showing a different method of attaching the shade 35 roller to the frame and illustrating the form of shade guide preferably used in such a case;

Fig. 5 is a perspective view of one of the guides detached from the frame; and,

40 Fig. 6 is an elevation of the same partly in section.

Referring more particularly to the drawing, it will be seen that this improved curtain guide may be constructed in several 45 different forms, all of which embody the same features. One of such forms is illustrated in Figs. 1 to 3, in which a guide to be used when the shade roller is set between the sides of the window frame is shown. It 50 is obvious that two of these guides are used, one on each side of the window shade, but in describing the invention, only one will be referred to for the sake of convenience. The form shown in the above mentioned 55 figures comprises a supporting member 1 preferably formed from a single strap of

metal having its intermediate portions extended outwardly as shown at 2, the ends of the strap being apertured as shown at 3 to provide attaching means whereby the 60 same may be secured to the side of the window frame. As shown in the drawing, the offset portion 2 is parallel to the plane of the attaching portions and has a laterally swinging arm 4 pivoted thereto as at 5. 65 This arm 4 carries an additional arm 6 which extends at right angles therefrom and is preferably made integral therewith, said arm 6 being provided with a slot 7 to receive one edge of the window shade.

The arm 4 is pivoted to the supporting member 1 to facilitate the raising and lowering of the window shade, since said shade when either moved upwardly or downwardly, is pulled toward the operator rather 75 than straight downwardly in the vertical plane of the roller. The curtain or shade can thus be moved in the slotted arm 6 without danger of tearing or otherwise injuring the edge of the same. The movement of the 80 swinging arm, however, is limited in both directions by a stop pin 8 carried thereby which is disposed in an arcuate slot 9 formed in the offset portion 2 of the supporting member. The pin 8 is placed near the rear 85 edge of the arm 4 to allow the same to be swung outwardly at a considerable angle, and yet prevents the same from moving inwardly past the vertical plane occupied by the supporting member.

As a further means for preventing the mutilation of the edges of the window shade or curtain, an upright flange 10 is formed on each opposite wall of the slot 7, thus forming a contact surface considerably 95 greater than the thickness of the arm 6. These flanges are preferably although not necessarily formed from the metal struck from the slot 7 and are extended upwardly above the arm.

In Figs. 4 to 6, a curtain guide is shown which is used when the shade roller is supported in brackets attached to the outer sides of the window frame. This form has a supporting member 11 which comprises 105 an attaching arm 12 and a guide carrying arm 13 formed integrally therewith and extended at right angles thereto, the attaching arm being provided with apertures 14 for fastening elements and the other arm carrying a laterally swinging right angular guide member 15. The member 15 is pivoted at 110

the upper end of its upright arm 16 adjacent the upper edge of the arm 13. The arm 16 carries a stop pin 17, one end of which is disposed in an arcuate slot 18 formed in the arm 11 of the supporting member 13, thereby limiting the swinging movement of the guide member 15. The slot is so disposed in the arm 13 that the member 15 is permitted to swing outwardly at an angle 10 to the vertical plane of the window shade, but is prevented from swinging inwardly past this plane.

The horizontal arm 19 of the guide member 15 is preferably formed integral with the vertical arm 16 thereof and is provided with a slot 20 in which the edge of the window shade S is disposed and guided. The opposite walls of this slot 20 are also provided with upright flanges 21 similar to and used 20 for the same purpose as the flanges 10 in the first-described form.

With either of these guides, it is obvious that the window shade will be effectively guided during its movement so that it will be wound upon the roller in the proper manner, and by providing one portion of the device with the swinging arm, the operation of the curtain will be greatly facilitated. Furthermore, the flanges formed adjacent 30 the walls of the slots will prevent the edges of the curtains upon which the device is used from becoming frayed or torn. The slots in the swinging arms of the guides are preferably made in such width that they 35 will prevent the enlarged lower end of the shade which usually contains a wooden strip

or other strengthening rod from passing through the same and thus preventing the curtain or shade from rolling up around the roller to such an extent that it might become necessary to remove the roller and rewind the spring. 40

I claim as my invention:

In a device of the class described, a bracket having a vertically disposed flat 45 face and means for securing said bracket to a support, a flat strip of metal bent at right angles at a point substantially midway its length to form vertical and horizontal flat arms, the vertical flat arm having a pivot 50 opening near its lower end, a pin fixed in said vertical flat arm at a point near the pivot opening, the horizontal flat arm being slit centrally from its free end to a point near the vertical arm, the material on the 55 edges of the slit being bent upwardly and outwardly to form curved flanges, the vertically disposed face of the bracket having a pivot opening near its lower end and an arcuate slot spaced from and concentric with said 60 pivot opening, a bolt extending through the aforesaid pivot openings to pivotally connect the bracket and vertical flat arm, and a pin in the vertical arm extending through and guided in the aforesaid arcuate slot. 65

In testimony whereof I have hereunto set my hand in presence of two subscribing witnesses.

WILLIAM M. MURRAY.
